SECTIONAL CABINET

Ed Bergman, New York, N. Y., assignor to Art Steel Company, Inc., Bronx, N. Y., a corporation of New York

Application September 1, 1939, Serial No. 292,967

7 Claims. (Cl. 312—107)

The present invention relates to sectional file cabinets made up of interchangeable units or sections which are adapted to be removably arranged one on top of the other to form a cabinet.

5 The present invention relates to means for aligning one section of such a cabinet upon another and locking the sections together.

The present invention contemplates the provision with such cabinet sections of locking and 10 aligning means which are adapted to be retracted within the sections so that when the lowermost section is arranged upon a flat surface such as upon a desk or floor the locking means are retracted out of the way and will not cut into or 15 scratch the surface on which they are arranged while the bottom of the section rests directly and solidly on the surface.

20 The present invention further contemplates the provision of sections having such locking means which are adapted upon arrangement of one section over the other to automatically align and lock the sections together.

25 The present invention further contemplates the provision of such sections and associated aligning and locking means which are simple and inexpensive in construction and which are durable in use.

30 Other and further uses and advantages of the present invention will become apparent from the following description and the drawing in connection therewith, in which:

35 Fig. 1 is a side elevational view, partly broken away, of a file cabinet comprised of two sections and illustrates a preferred embodiment of the present invention.

Fig. 2 is a fragmentary perspective view of a portion of the rear of the cabinet illustrated in Fig. 1 showing the rear aligning and locking means.

40 Fig. 3 is a perspective view of a portion of the front of the cabinet illustrated in Fig. 1 showing the front aligning and locking means.

45 Referring now to the drawing in Figure 1 a cabinet of two sections is illustrated, having an upper section 10 and a lower section 12, which are each preferably identical in construction. While I have illustrated my invention with two sections stacked one on top of the other, it is to be understood that the number of sections which 50 may be arranged on top of each other is unlimited.

55 The entire sectional cabinet may be arranged on a surface such as a desk top or a floor 14, on which the lower section 12 rests. Each section is comprised of the conventional top wall 16, bottom wall 18, side walls 20 and rear wall

22. Arranged to move within these walls is the conventional drawer 24. It is unnecessary to describe the details of construction of the sections, for an understanding of my invention, which may be applied to any type of file cabinet 5 section.

The walls 16, 18 and 20 may be provided with the conventional means for guiding the movement of the drawer 24 in and out of the section. An L-shaped flange 26 is preferably secured at the 10 front ends of the section to the top and bottom walls 16 and 18 against which the drawer 24 slides when withdrawn from the section.

While the cabinet sections heretofore described are preferably made of sheet metal, it is to be 15 understood, of course, that other materials may be employed, and that the present invention is applicable to wooden cabinets and cabinets made of other materials as well.

For the purpose of aligning and securing one 20 section to another, I prefer to provide a spring-like rear aligning latch 28 at the bottom of each section at the rear thereof. The rear aligning latch 28 may be made of a flat spring-like plate of ordinary steel or spring steel, although it is 25 preferred that ordinary cold rolled steel be employed. The spring-like action is obtained by making the flat portion of the latch sufficiently long so that the end thereof has a substantial lift. One end thereof is preferably bent to form 30 a V-shaped hook 30. The rear aligning latch 28 is preferably arranged centrally of the section near the bottom thereof adjacent the rear wall 22. The rear latch 28 is secured at the end of the flat spring portion thereof opposite the hook 35

30 to the bottom reenforcing plate 32 which runs across the bottom of the section adjacent the rear thereof. The aligning latch 28 may be secured to the bottom reenforcing plate 32 by means of two spot welds 34 at the end thereof opposite the hook-like portion 30. Of course, it is to be understood that rivets and other methods might be used to secure said rear aligning latch to the rear reenforcing plate 32. When the rear latch is secured to the reenforcing plate, 40 the end of the hook 30 is disposed downwardly.

To accommodate the hook 30, a portion of the rear wall 22 adjacent the hook 30 is cut away to provide an opening 36 therein, and portions of the reenforcing plate 32 and the bottom 18 adjacent said hook are cut away to provide an opening 38 which joins with the opening 36 in the rear wall. 45

The end of the hook 30 tends to move downwardly through the bottom opening 38 urged by 50 55

The end of the hook 30 tends to move downwardly through the bottom opening 38 urged by 55

the spring tension of the latch 28. However, as will be seen in Figure 1 in connection with the lower section 12, when said section is arranged directly on a flat surface 14 the end of the hook-like portion 30 is pushed upwards and the hook-like portion assumes the position so that the lowermost end thereof is on a level with the bottom wall 18 of the section and the section assumes a level position thereon.

- 10 When one section is arranged on top of another, the rear latch 28 on the upper section is adapted to engage the lower section to align and lock the upper section to the lower.
- For the purpose of engaging the rear latch, a 15 rectangular slot 42 may be provided in the top of each section at the rear thereof. This rear slot 42 is formed by cutting away a narrow portion of the top 16 of each section at the rear of said top and an adjacent narrow portion of the 20 rear wall at the top thereof. The upper rear slot 42 is located centrally of the section and is shaped and positioned to receive therein the hook 30 of the rear latch 28 of the section 10 immediately above.

- 25 In arranging one section over another, the top section 10 is placed over the lower section 12 so that the rear of the top section 10 is a little bit in back of the rear of the lower section 12 and by pulling the top section forward, the hook 30 of the rear aligning latch 28 will enter the upper 30 rear slot 42 of the lower section 12 and will be hooked securely therein, thus aligning the top section with the lower section. The two sections will be so secured together that the top section 35 10 will not be able to be moved forward relative to the lower section 12.

To cooperate with the rear aligning latch 28 in aligning and locking the sections together, a front aligning latch 44 may be provided. The 40 front aligning latch 44 may be made of a flat spring-like plate of the same material as the rear aligning latch and may be also centrally located, being preferably, however, adjacent the front of the section and secured to the front reinforcing plate 46 by its flat spring-like portion 48. The front reinforcing plate 46 may be provided near the front of the cabinet running across the bottom thereof and is adapted to strengthen the structure. It is to be understood, of course, that both the front latch 44 and the rear latch 28 may be secured directly to the bottom of the cabinet instead of to their respective reinforcing plates 48 and 32. From the flat portion 48, a flange or lip 50 is formed 45 at one end thereof at substantially right angles thereto. The lip 50 is adapted to enter an opening 52 formed in the bottom 18 of the section and passing through the front reinforcing plate 46.

- 50 When one section is arranged on a lower section, the front latch 44 of the upper section is adapted to engage the lower section by means of lip 50 to align the sections and secure them fixedly together. To cooperate with the lip 50, a 55 rectangular front slot 54 may be provided in the top of each section of the proper size, shape and location to receive and accommodate the lip 50.

When the upper section 10 is arranged on the 60 lower section 12, the springiness of the flat portion 48 of the latch 44 forces the lip 50 to enter the front slot 54 in the top of the cabinet section below. When, however, the particular section is arranged directly on a flat surface, the lip 50 is forced by the surface to reenter within

the section so that the end of the lip is on a level with the bottom of the section and the bottom of the section rests directly on the flat surface.

From the foregoing description, it will be seen 5 that to arrange one section 10 upon the lower section 12 the upper section is first placed upon the lower section with the rear of the upper section projecting rearwardly of the rear of the lower section. The upper section is then moved 10 forward and the hook 30 of the rear aligning latch 28 enters the rear slot 42, and the lip 50 of the front aligning latch 44 enters the cooperating front slot 54 in the top near the front of the section. The two sections are, therefore, 15 locked together and properly aligned.

When it is desired to remove the upper section from the lower section, the lip 50 of the front latch 44 is manually lifted out of the front slot 54 and the upper section is moved rearwardly so as to cause the hook 30 of the rear aligning latch 28 to move out of the rear slot 42.

It is preferred that said slots 42 and 54 be made rectangular in shape and wide, and that the latches be made of narrow but fairly wide rectangular plates which fit closely into the slots, in order that the maximum amount of surface might be provided to prevent relative movement of the sections such as twisting.

It will be understood that each of the sections is of the same construction so that they may be interchangeably used in the formation of a sectional file cabinet.

While I have described in specific detail a preferred embodiment of the present invention, 35 it must be understood that various modifications may be made in respect thereto without departing from the spirit of the present invention, and, therefore, that I intend to be limited solely by the state of the prior art and the scope of the 40 appended claims.

I claim:

1. A sectional file cabinet comprising in combination a plurality of interchangeable sections removably stacked one upon the other, the lowermost section adapted to be arranged upon a support, each section having top and bottom walls, the bottom wall of each section having an opening therein, an aligning latch comprising a flat spring member arranged adjacent the bottom wall and an integral lip extending downwardly from the spring member and projecting through said bottom wall opening, the lip urged outwardly through the opening by the flat spring member, a slot in the top wall of each section arranged to accommodate the lip projecting through the bottom wall opening of the section stacked immediately above, the lip being urged into the slot by the flat spring member to thereby align the sections and secure them against 60 lateral movement relative to each other, the lip of the lowermost section being urged inwardly within the section by the support upon which said lowermost section is arranged whereby the bottom wall of the said lowermost section rests 65 directly on the said support.

2. A sectional file cabinet comprising in combination a plurality of interchangeable sections removably stacked one upon the other, the lowermost section adapted to be arranged upon a 70 support, each section having top and bottom walls, the bottom wall of each section having an opening adjacent the rear thereof and an opening adjacent the front thereof, a rear aligning latch comprising a tension member arranged 75

adjacent the bottom wall and a hook extending from the tension member and projecting through the rear bottom wall opening, the hook urged outwardly through the opening by the tension member, a forward aligning latch comprising a tension member and a lip extending from said member and projecting through the forward bottom wall opening, the lip urged outwardly through said opening by the tension member, a slot in the top wall of each section at the rear thereof, the hook projecting through the rear bottom wall opening of the section immediately above being arranged within the rear slot, and a slot in the top wall of each section near the forward end thereof, the lip projecting from the forward bottom wall opening of the section immediately above being arranged within the forward slot to thereby align the sections and secure them against lateral movement relative to each other, the lip and hook of the lowermost section being urged inwardly within the section by the support upon which the said lowermost section is arranged whereby the bottom wall of the lowermost section rests directly on the support.

3. A sectional file cabinet comprising in combination a plurality of interchangeable sections removably stacked one upon the other, the lowermost section adapted to be arranged upon a support, each section having top and bottom walls, the bottom wall of each section having an opening therein, an aligning latch comprising a tension member arranged adjacent the bottom wall and a lip extending downwardly from the tension member and projecting through said bottom wall opening, the lip urged outwardly through the opening by the flat spring member, a slot in the top wall of each section arranged to accommodate the lip projecting through the bottom wall opening of the section stacked immediately above, the lip being urged into the slot by the tension member to thereby align the sections and secure them against lateral movement relative to each other, the lip of the lowermost section being urged inwardly within the section by the support upon which said lowermost section is arranged whereby the bottom wall of the lowermost section rests directly on the support.

4. A sectional file cabinet comprising in combination a plurality of interchangeable sections adapted to be removably stacked in alignment one upon the other, the lowermost section of the sectional file cabinet adapted to be arranged upon a support, each section having top and bottom walls, the bottom wall of each section having an opening therein adjacent the rear of said section, an aligning latch associated with each section comprising a flat spring member secured to the bottom wall of said section with which said aligning latch is associated, and an integral hook extending from the said spring member and projecting through said bottom wall opening of the said section, the hook urged outwardly through the said opening by the flat spring member, a slot in the top wall of each section at the rear thereof arranged to receive the hook projecting through the bottom wall opening of the section stacked immediately above, the said hook being received in the said slot in the top wall of the section below upon stacking the upper section upon the lower section to thereby align the sections relatively to one another, said hook cooperating with the slot to secure the sections against lateral movement relative to each other, the hook of the lowermost

section being urged inwardly within the section by the support upon which it is arranged whereby the bottom wall of the lowermost section rests directly on the support.

5. An interchangeable cabinet section for a sectional file cabinet made up of said interchangeable sections and which are adapted to be removably arranged one on top of the other to form the sectional file cabinet, said interchangeable cabinet section having a top, bottom and rear wall, the bottom wall having an opening therein adjacent the rear wall, said rear wall having an opening therein extending to and in communication with the opening in the said bottom wall, an aligning latch comprising a tension member secured to the bottom wall and extending through the said opening in the rear wall and a hook member extending from the tension member and projecting through the bottom wall opening, the hook urged outwardly through the said bottom wall opening by the tension member, said top wall having an opening adjacent the rear wall, said rear wall having a second opening extending into and in communication with the opening in the top wall, said top wall and second mentioned rear wall opening being in alignment with the bottom wall and first mentioned rear wall openings and of dimensions corresponding to said hook.

6. An interchangeable cabinet section for a sectional file cabinet made up of said interchangeable sections and which are adapted to be removably arranged one on top of the other to form said sectional file cabinet, said interchangeable cabinet section having a top and a bottom wall, the bottom wall having an opening therein and an aligning latch comprising a flat spring member secured to the bottom wall and an integral lip extending downwardly from the spring member and projecting through said bottom wall opening, the lip urged outwardly through the opening by the said flat spring member, the top wall having arranged therein a slot, said slot on the top wall being in alignment with the opening in the bottom wall and of dimensions corresponding to the said lip.

7. An interchangeable cabinet section for a sectional file cabinet made up of said interchangeable cabinet sections and which are adapted to be removably arranged one on top of the other to form said sectional file cabinet, said section having a top and a bottom wall, the bottom wall having an opening adjacent the rear of the cabinet section and an opening adjacent the front of the cabinet section, a rear aligning latch comprising a tension member secured to the bottom wall and a hook extending from the tension member and projecting through the rear bottom wall opening, the hook urged outwardly through the said rear bottom wall opening by the tension member and a front aligning latch comprising a tension member and a lip extending from said member and projecting through the front bottom wall opening, the said lip urged outwardly through said front bottom wall opening by the tension member, said top wall having a slot at the rear of the cabinet section in alignment with the rear bottom wall opening and of dimensions corresponding to said hook, said top wall having a second mentioned slot adjacent the front of the cabinet section and in alignment with the front bottom wall slot and of dimensions corresponding to the said lip.

ED BERGMAN.
